UNITED STATES PATENT OFFICE.

THOMAS E. SMITH, OF LOS ANGELES, CALIFORNIA, ASSIGNOR TO ENDERT TRAFFIC SIGNAL COMPANY, OF BAKERSFIELD, CALIFORNIA, A CORPORATION OF CALIFORNIA.

SWITCH.

1,300,665.

Specification of Letters Patent. Patented Apr. 15, 1919.

Application filed June 18, 1917. Serial No. 175,345.

To all whom it may concern:

Be it known that I, THOMAS E. SMITH, a citizen of the United States, residing at Los Angeles, in the county of Los Angeles, 5 State of California, have invented new and useful Improvements in Switches, of which the following is a specification.

This invention relates to electrical switches and relates particularly to a switch 10 adapted for use in connection with signals or indicators. Although I do not limit my invention to such particular uses, I explain my switch in its use as a control switch for an automobile signal or direction indicator.

One of the particular objects of my invention is to provide a switch of simple design, construction and operation; and to 15 provide a switch whose operation is of a simple and natural character. In accomplishing this object I provide a switch completely actuated through the medium of a single handle; different movements of this handle causing different actuations of the switch mechanism. For instance, in an 20 automobile direction indicator it is desirable to have an indicator mechanism which is capable of signaling "Stop", "Right" and "Left". In coöperation with such a signal, my switch is arranged so that a rearward movement of the handle will cause the 25 actuation of the switch mechanism to show the signal "Stop", while a movement, preferably of rotation of the handle to the right or left will cause the signal mechanism to 30 show the indication "Right" or "Left".

Further objects of my invention, and the invention itself, will now be best understood from the following detailed description of a preferred specific form of switch embodying 35 the invention. For the purpose of this indicative specification I refer to the accompanying drawings in which Figure 1 is a side elevation of my improved switch; Fig. 40 2 is a bottom plan thereof; Fig. 3 is a detail section taken as indicated by line 3-3 on Fig. 1; Fig. 4 is a detail section taken as 45 indicated by line 4-4 on Fig. 1; Fig. 5 is a top plan of the switch; Fig. 6 is a plan showing the switch within its case; and Fig. 50 7 is a diagram illustrating the electrical connections of the switch.

I provide a convenient base 10, preferably of sheet metal, having securing lugs 11 by which the switch may be fastened to any

part of an automobile in convenient position before the driver. Upon this base I mount the switch mechanism 12 and the indicator lamps 13 and 14. The switch mechanism 12 comprises three stationary contacts 15, 16 and 17 and a movable switch 55 arm 18, the movable arm being mounted upon a switch rod 19 mounted in a bearing block 20 and bearing member 20^a and adapted to be movable both rotatively and longitudinally. A torsion spring 21 is 60 placed around rod 19 and has its ends 21^a and 21^b depending on opposite sides of a member 22 set on the rod and on opposite sides of a member 23 on the base 10. Rotation of the rod in either direction causes 65 one end of the spring to be carried around by member 22 while the other is held by member 23; and the spring thus acts to return the rod to its normal position regardless of the direction of rotation. 70

The switch arm 18 projects above the switch rod 19 and also slightly below the switch rod 19, as shown at 18^a; and when the handle 19^a is pulled out in the direction indicated, this lower part 18^a of the switch 75 rod rides upon the raised outer end 17^a of the stationary contact 17, making electrical connection therewith. When the parts are in this position just described, then a screw, or other member shown at 24 on the rod 19 80 moves into a slot 25 in bearing block 20 to prevent the rotation of the switch arm when it is moved out longitudinally; so as to prevent the mechanism from being operated by longitudinal movement and by rotation at 85 the same time. This screw striking the end of the slot 25 also limits the outward movement of the rod to that amount of movement which is necessary to engage the part 90 18^a with the part 17^a.

With the switch rod in its normal longitudinal position it may be rotated over to the right or left so that the normally upper end of the arm 18 will move over and strike either the stationary contact 15 or the stationary contact 16. Spring 21 opposes this movement and brings the switch mechanism back to its normal position when handle 23 is released. It will be seen that, by simple and natural movements of the handle 23, 100 the switch arm 18 may be engaged with any one of the stationary contacts 15, 16 and 17. Stationary contacts 15, 16 and 17 are formed 105

of spring sheet metal and are held in a built up block 30 of insulating material. The contacts 15 and 16 are turned up so as to lie in the relative positions shown in Fig. 3; so that the rod 19 and arm 18 need not be turned through a great angle to engage them.

The various wires 32, 33, 34, 35, 36 and 37 make connections as follows: Wire 32 is connected to stationary contact 15; wire 33 is connected to stationary contact 17; wire 35 is connected to stationary contact 16; wire 34 is connected through the block 30 and through a spring wire coil 34^a to the switch arm 18. This coil 34^a serves as an electrical connection and at the same time resiliently resists the outward movement of the switch rod. Wire 36 is connected to lamp 13 and wire 37 is connected to lamp 14; the other 10 sides of these lamps being connected through wires 38 and 39 to ground at 40. For the purposes of this specification, and for purposes of explaining this switch invention, it is not necessary to enter into the details of 15 an indicator mechanism nor to enter into details of the circuits of those mechanisms. These things are, generally, and in a preferred and specific form, explained in my application on automobile signals co-pending 20 herewith, bearing Serial No. 175,344, filed June 18, 1917. It will be sufficient herein to say that the general circuiting arrangement includes the connection of the wire 34 to a battery at 41, the other side of 25 the battery being preferably grounded at 42. Moving handle 19^a to the left and sending current out through the wire 32 causes the signal mechanism or mechanisms to indicate "Left"; moving handle 19^a back longitudinally and sending current out through 30 wire 33 causes the signal mechanism to indicate "Stop", and moving handle 19^a to the right and sending current out through wire 35 causes the signal mechanism to indicate "Right". The handle 19^a is arranged, in any particular placement of the switch, to stand normally vertically. The lamps 13 and 14 are connected into the signal systems in such a manner that when the signals are 35 operated, then these lamps 13 and 14 are illuminated, all as described in my co-pending application.

The switch mechanism itself is the subject matter of the present application and the 40 subject matter of the following claims. I believe my invention to be broad in its nature, as appertaining to switches; and I therefore do not limit myself to specific details and particular constructions as herein 45 described, regarding this specific and particular construction as indicative of my invention in its various possible forms. The following claims are therefore drawn to cover the invention broadly as well as specifically.

Having described a preferred form of my invention, I claim:

1. A switch mechanism, comprising a switch arm adapted to be moved along a longitudinal axis and adapted to be rotated in either direction of rotation about said axis, three stationary contacts arranged spacedly about said axis, one of said contacts being longitudinally spaced from the other two in such arrangement that a longitudinal movement of said switch arm causes engagement with said first mentioned contact and a rotation of said switch arm causes engagement with either one or the other of the other two contacts, and means to prevent rotation of the switch arm when it is longitudinally moved from its normal position. 70

2. A switch mechanism embodying a base, a switch rod mounted thereon to be independently longitudinally slidable and rotatable, spring means to oppose the longitudinal and rotational movements of the switch rod, a switch arm mounted transversely across the end of the switch rod extending normally both above and below the switch rod, a stationary contact below the switch rod in a position to be engaged by the lower end of the switch arm when the switch rod and arm are moved longitudinally, and a pair of stationary contacts arranged at opposite sides of the switch rod and with which the upper end of the switch arm is adapted to engage when the switch rod and arm are rotated. 80

3. A switch mechanism embodying a base, a switch rod mounted thereon to be independently longitudinally slidable and rotatable, spring means to oppose the longitudinal and rotational movements of the switch rod, a switch arm mounted transversely across the end of the switch rod extending normally both above and below the switch rod, a stationary contact below the switch rod in a position to be engaged by the lower end of the switch arm when the switch rod and arm are moved longitudinally, a pair of stationary contacts arranged at opposite sides of the switch rod and with which the upper end of the switch arm is adapted to engage when the switch rod and arm are rotated, and means to prevent rotation of the switch rod and arm when they are moved longitudinally from their normal position. 90

4. A switch mechanism, comprising a base, journal blocks mounted on said base, a switch rod mounted in said journal blocks and movable independently both longitudinally and rotatively therein, said longitudinal movement being outward away from the base, spring means connected to the base and to the switch rod to oppose longitudinal and rotative movements of the switch rod, means to prevent rotation of the switch rod when 100

it is moved outwardly from its normal longitudinal position, said means embodying a projecting member on the switch rod and a slot in one of the journal blocks adapted to 5 be entered by said projecting member, a switch arm mounted transversely across the end of the switch rod and projecting both above and below the switch rod in normal position, a stationary contact below the 10 switch rod and arm and adapted to be engaged by the lower end of the switch arm when moved longitudinally outwardly, and a pair of stationary contacts arranged on horizontally opposite sides of the switch 15 rod and adapted to be engaged by the upper end of the switch arm when rotated in one direction or the other.

5. A switch mechanism, comprising a base, journal blocks mounted on said base, 20 a switch rod mounted in said journal blocks and movable independently both longitudinally and rotatively therein, said longitudinal movement being outward away from the base, spring means connected to the base 25 and to the switch rod to oppose longitudinal

and rotative movements of the switch rod, means to prevent rotation of the switch rod when it is moved outwardly from its normal longitudinal position, said means embodying a projecting member on the switch rod and 30 a slot in one of the journal blocks adapted to be entered by said projecting member, a switch arm mounted transversely across the end of the switch rod and projecting both above and below the switch rod in normal 35 position, a stationary contact below the switch rod and arm and adapted to be engaged by the lower end of the switch arm when moved longitudinally outwardly, a pair of stationary contacts arranged on horizontally opposite sides of the switch rod and adapted to be engaged by the upper end 40 of the switch arm when rotated in one direction or the other, and a contact carrying block in which the three stationary contacts 45 are mounted and carried.

In witness that I claim the foregoing I have hereunto subscribed my name this 11th day of June, 1917.

THOMAS E. SMITH.
